(57) CLAIM

The ornamental design for a tote bag, as shown and described.

DESCRIPTION

FIG. 1 is a left-front, perspective view of a tote bag of our new design;

FIG. 2 is a front view of our new design;

FIG. 3 is a back view of our new design, the upper strap attachment behind the strap is the mirror image of the lower strap attachment depicted;

FIG. 4 is a right-side view of our new design;

FIG. 5 is a left-side view of our new design;

FIG. 6 is a top view of our new design;

FIG. 7 is a bottom view of our new design; and,

FIG. 8 is a front view of our new design, with the tote bag in the open configuration.

In FIGS. 1-7, the strap is part of the claimed design, but not its arrangement in the figures. By “arrangement” we do not mean its design or constituent elements, but the shape of the strap as it is depicted in the figures.
